[57] CLAIM

The ornamental design for a beverage container holder, as shown and described.

DESCRIPTION

FIG. 1 is a perspective view of the beverage container holder in accordance with the present design;

FIG. 2 is a top plan view thereof;

FIG. 3 is a bottom plan view thereof;

FIG. 4 is a side elevational view thereof;

FIG. 5 is an end view thereof;

FIG. 6 is a front view thereof;

FIG. 7 is a perspective view of a second embodiment of the design;

FIG. 8 is a top plan view thereof;

FIG. 9 is a bottom plan view thereof;

FIG. 10 is a side elevational view thereof;

FIG. 11 is an end view thereof;

FIG. 12 is a front view thereof;

FIG. 13 is a perspective view of a third embodiment of the design;

FIG. 14 is a top plan view thereof;

FIG. 15 is a bottom plan view thereof;

FIG. 16 is a side elevational view thereof;

FIG. 17 is an end view thereof;

FIG. 18 is a front view thereof;

FIG. 19 is a perspective view of a fourth embodiment of the design;

FIG. 20 is a top plan view thereof;

FIG. 21 is a bottom plan view thereof;

FIG. 22 is a side elevational view thereof;

FIG. 23 is an end view thereof; and,

FIG. 24 is a front view thereof.
